UNITED STATES PATENT OFFICE.

ZACHRY T. FURBISH, OF PHILADELPHIA, PENNSYLVANIA, ASSIGNOR TO
NORTH BROTHERS MANUFACTURING COMPANY, OF PHILADELPHIA,
PENNSYLVANIA, A CORPORATION OF PENNSYLVANIA.

PUSH-DRILL.

SPECIFICATION forming part of Letters Patent No. 791,767, dated June 6, 1905.

Application filed September 22, 1903. Serial No. 174,211.

To all whom it may concern:

Be it known that I, ZACHRY T. FURBISH, a citizen of the United States, residing in Philadelphia, Pennsylvania, have invented certain 5 Improvements in Push-Drills, of which the following is a specification.

The object of my invention is to so construct a push-drill that the spring can be adjusted so that more or less tension can be applied, 10 according to the size of drill used and the character of material to be drilled.

In a pending application for patent, filed on the 12th day of September, 1903, Serial 15 No. 172,940, I have claimed, broadly, a push-drill having means for adjusting the spring, while the present invention relates to means located at the handle end of the tool for adjusting the spring.

In the accompanying drawings, Figure 1 is 20 a side view of my improved push-drill. Fig. 2 is a longitudinal sectional view. Fig. 3 is a transverse sectional view on the line 3 3, Fig. 2. Fig. 4 is a transverse sectional view 25 on the line 4 4, Fig. 2. Fig. 5 is a transverse sectional view on the line 5 5, Fig. 2. Fig. 6 is a perspective view of the adjusting-screw. Fig. 7 is a sectional perspective view of the 30 handle, showing the magazine; and Fig. 8 is a sectional perspective view of the cap.

A is the handle of the push-drill, and mounted on the end of the handle is a magazine-section A', having a head A², which is screwed into the end of the tube which forms the handle.

B is a carrier arranged to slide and turn in the handle A. A portion b' of the carrier is screw-threaded, and the screw meshes with a nut a², secured to the handle, so that when pressure is placed upon the handle the carrier will be turned. At the outer end of the carrier in the present instance is a chuck b.

A spring D extends through the carrier and into the handle and rests against a nut d on a screw-stem D'. The nut d has a spline d³, 45 which enters a slot e in a tube E, secured to the head A². The screw-stem D' has its bearing in the head A² and is secured to a cap d²,

so that on turning the cap the screw will be turned, causing the nut d to travel, either compressing the spring or allowing it to expand. 50

The magazine A' has a number of compartments a for the drills. These compartments are formed by radial partitions, as shown in Figs. 3 and 4. One of the compartments is 55 filled with a grooved block, in which slides a bolt I, extending to the cap d² and entering one of a series of holes in the cap. A flanged ring f forms the bottom of the compartments a of the magazine and is supported by a spring F, which rests against a washer i in the end of the handle. The washer enters a notch in the bolt I, so that the spring acts to force the bolt into the holes in the cap d². When the bolt is withdrawn, the washer rocks, and as 60 soon as the bolt is released the spring acts to throw the bolt.

Sliding on the handle A is a cap-ring H, which forms a closure for the magazine, as shown in Fig. 2. This cap-ring has a portion 70 h, which extends into the magazine, and has a screw-threaded portion h', on which is a flanged nut h². Between the flange of the nut and the end of the cap is a spring-ring h³.

Cut in the handle A is an annular groove, 75 into which the ring h³ is forced by screwing up the nut when it is wished to fasten the cap-ring H in position closing the magazine. As soon as the nut is backed off the ring will spring out of the groove and release the cap, 80 so that it can be withdrawn from the magazine sufficiently to allow the drills to be projected by the spring F to enable any one of the drills to be removed. Other means of fastening the cap-ring to the handle may be 85 employed without departing from the main feature of my invention.

When it is wished to drill soft material or use a small drill, the nut is backed off by turning the cap at the end of the handle so that the spring is under very little tension; but when a large drill is used or hard material is to be drilled then the nut is forced against the spring by turning the cap until the spring 90

is compressed to the proper degree. By regulating the tension of the spring proper resistance is given to the pressure against the handle.

5 I claim as my invention—

1. The combination in a push-drill, of a handle, a carrier, a spring resting against the carrier, and a screw carried by the handle for adjusting the spring, substantially as described.

10 2. The combination of a handle, a tubular carrier, a spring within the carrier and extending into the handle, a screw extending from the handle into the spring, a nut on the screw, means for preventing the nut turning, and a

15 cap secured to the screw and by which it is turned to adjust the nut longitudinally, substantially as described.

20 3. The combination of a handle, a carrier mounted in the handle, a nut on the handle

25 and a screw-thread on the carrier so that when the handle is reciprocated the carrier will be turned, a spring mounted in the carrier and extending into the handle, a screw projecting from the handle, a cap secured to the screw forming the end of the handle, a nut on the screw, a slotted tube engaging the nut so that when the screw is turned the nut will move longitudinally and adjust the spring, substantially as described.

30 4. The combination in a push-drill, of a handle, a carrier, a spring resting against the carrier, a screw mounted in the handle of the drill, and a cap on the handle to which the screw is attached so that on turning the cap

the spring can be adjusted, substantially as described.

5. The combination in a push-drill, of a handle, a carrier, a spring resting against the carrier, a nut bearing against the spring, a screw within the handle arranged to pass through the nut, a cap on the end of the handle attached to the screw, and a latch for locking the cap in the adjusted position, substantially as described.

40 6. The combination of a handle, a screw- 45 stem mounted therein, a cap secured to the screw-stem, a carrier, a spring, a nut on the screw - stem, a bolt for locking the cap, a washer in the handle engaging the bolt, and a spring bearing against the washer, substan- 50 tially as described.

7. The combination of a handle, a screw- 55 stem mounted therein, a cap secured to the stem, a carrier, a spring, a nut on the screw-stem, a magazine surrounding the handle, a ring on the handle forming the bottom of the magazine, a bolt for locking the cap to the handle, a washer in the handle engaging the bolt, and a spring mounted in the handle between the ring and the washer, substantially 60 as described.

In testimony whereof I have signed my name to this specification in the presence of two subscribing witnesses:

ZACHRY T. FURBISH.
